(57) **CLAIM**

The ornamental design for a bird feeder with camera, as shown and described.

DESCRIPTION

- FIG. 1 is a front elevation view of a bird feeder with camera showing the new design;
FIG. 2 is a back elevation view thereof;
FIG. 3 is a left-side view thereof;
FIG. 4 is a right-side view thereof;
FIG. 5 is a top plan view thereof;
FIG. 6 is a bottom plan view thereof;
FIG. 7 is a perspective view thereof;
FIG. 8 is another perspective view thereof; and,
FIG. 9 is another perspective view thereof.
The broken lines depict portions of the article that form no part of the claimed design.
